UNITED STATES PATENT OFFICE.

WILLIAM H. SCOTT, OF ST. LOUIS, MISSOURI, ASSIGNOR TO CHICAGO RAILWAY EQUIPMENT COMPANY, OF CHICAGO, ILLINOIS, A CORPORATION OF ILLINOIS.

TRUCK-BOLSTER.

SPECIFICATION forming part of Letters Patent No. 762,443, dated June 14, 1904.

Application filed March 19, 1904. Serial No. 198,912. (No model.)

To all whom it may concern:

Be it known that I, WILLIAM H. SCOTT, a citizen of the United States, residing at St. Louis, Missouri, have invented a certain new and useful Improvement in Truck-Bolsters, of which the following is a full, clear, and exact description, such as will enable others skilled in the art to which it appertains to make and use the same, reference being had to the accompanying drawings, forming part of this specification, in which—

Figure 1 is a view, partly in elevation and partly in section, of a bolster constructed in accordance with my invention. Fig. 2 is a view partly in plan and partly in section. Fig. 3 is a sectional view on the line 3 3 of Fig. 1. Fig. 4 is a cross-sectional view on the line 4 4 of Fig. 1. Fig. 5 is a cross-sectional view on the line 5 5 of Fig. 1. Fig. 6 is a fragmentary central longitudinal view of a slightly-modified form of the invention, and Fig. 7 is a fragmentary view of a slightly-modified form of compression member.

This invention relates to truck-bolsters; and one of the objects thereof is to provide a bolster structure, the parts of which can be easily assembled and which will provide a maximum strength with a minimum weight.

With these and other objects in view the invention consists of certain novel parts and combinations of parts, to be referred to hereinafter, the novel features being particularly defined in the claims.

The compression member of the bolster is illustrated as comprising a plurality of I-beams 1, connected by a flat plate tension member 2, the ends of which are bent up to pass over the ends of the compression member, and these members are spaced apart and braced by a strut or king-post 3. In the form of bolster illustrated in Figs. 1, 2, 3, 4, and 5 there are but two I-beams employed, which I-beams are provided with terminally-disposed longitudinal slits 4, which are formed by removing portions of the webs of the I-beams, so that the adjacent edges of the slits can be brought together to restrict the ends

of the I-beams, so that their lower edges 5 will converge toward the upper edges 6 of the I-beams and provide contacting portions 50 adapted to rest upon the upper faces of the tension member 2. In order that the edges of the slotted portions of the respective I-beams can be brought together by suitable pressure and in order to prevent further splitting when 55 the parts are brought together, openings 7 are formed in the flanges, one at the end of each slit. By forcing the adjacent edges of the slits together, so as to give the proper inclination to the bottom flanges 5 of the I-beams, 60 an extended bearing-surface is provided, which is received by a corresponding part of the tension member 2, the ends of which are bent up over the respective ends of the I-beams and rest upon the top flanges 6 thereof. In 65 order to provide for the rigidity of the bolster, a filler-block 8 is interposed between the ends of the I-beams and the bend in the tension member, said filler-block having a portion 9 interposed between the webs of the respective I-beams, which portion 9 is provided with perforate lugs 10 for the reception of suitable fastening devices 11, which pass through the ends of the tension member and through the filler-block, so that the filler-block 70 can be securely held in place.

The strut or king-post is best illustrated in Figs. 1 and 4, in which it is shown as a casting having flanged seats 12 and 13 to receive the bottom flanges of the I-beams, the top 80 flanges of said I-beams being engaged by the flanged center bearing-plate 14, which serves as a clamp for securing the I-beams to the strut. The bottom of the strut is provided with a flanged seat 15, capable of straddling 85 the flat plate tension member 2, and said strut is provided with the usual central opening 16 for the reception of the king-bolt. The spacing portions 17 and 18 are carried by the strut and materially assist in spacing the I-beams 90 apart and in holding them rigid with relation to the remaining parts of the bolster.

The castings on the ends of the bolster are each designated by the reference-numeral 19,

and each consists of a casting having a fixed side bearing 20, forming a part thereof, and which bears upon the top edge or flange of each I-beam, the bottom edge of the casting resting upon and inclined coincidently with the flat plate tension member. At one end of each casting a seat 21 is formed to conform to the curvature of the bend. In the end of the flat plate tension member 2 the castings are secured to the bolster by fastening devices, illustrated as bolts 22 and 23, which pass through the casting and through the I-beams on the respective sides of the slit 4. Each fastening device passes through spacing-sleeves 24, which tend to hold the I-beams a suitable distance apart, said sleeves 24 being assisted in this by the strut 3 and the portion 9 of the filler-block 8. It will be observed that the side bearing 20 on each casting is formed as a part thereof and bears against the top flange of said compression member, the lower portion 5 resting against the under side of the tension member 2, whereby a clamping effect is produced to hold the parts against independent movement.

Within the spring-seat 25 is a wooden block 26, which is adapted to bear upon the supporting-springs for the bolster.

In Fig. 6 I have illustrated a slightly-modified form in which substantially the same principle is involved, the difference being that the casting carrying the usual spring-seat and column-guides is capable of being slipped over the ends of the compression member and tension member, said casting being provided with a shoulder 27 to be engaged by the edge of the upturned end of the tension member, whereby the casting will be held in place and the fastening devices 11^a serve the purpose of securing the casting to the bolster and in securing the compression member, the tension member, and the casting in rigid contact.

In Fig. 7 the ends of the compression members are reduced by corrugating the ends of the I-beams, as at 28, and thus obviating the necessity of slitting the ends of the beams. This is a commercial form of I-beam and can be easily substituted for the ones illustrated in Figs. 1 to 6 without the employment of special machinery.

By utilizing a plurality of I-beams a much lighter and stronger structure can be made than can be obtained by the use of the channel-iron usually employed in bolsters of this type.

Although this bolster is of considerably less weight than those ordinarily employed, its strength will be in no wise affected, as the peculiarly novel arrangement of I-beams and flat plate tension member provides an exceedingly strong and durable bolster, while requiring only a minimum amount of metal.

I am aware that minor changes in the construction, arrangement, and combination of the several parts of my device can be made

and substituted for those herein shown and described without in the least departing from the nature and principle of my invention.

Having thus described the invention, what is claimed as new, and desired to be secured by Letters Patent, is—

1. A bolster comprising an I-beam compression member, a flat plate tension member bent over the ends of the compression member, and a strut; substantially as described. 75

2. A bolster having a compression member comprising a plurality of I-beams, a flat plate tension member bent over the ends of the respective I-beams, and a strut; substantially as described. 80

3. A bolster comprising a compression member having tapered ends, and a flat plate tension member bearing against the under side of the compression member and bent over the ends to engage the top thereof; substantially as described. 85

4. A bolster comprising an I-beam compression member having tapered ends, and a flat plate tension member bearing against the under side of the compression member and bent over the ends to engage the top thereof; substantially as described. 90

5. A bolster comprising a compression member having longitudinal slits in its ends with the adjacent edges of the slits bearing one upon the other, a tension member engaging the respective ends of the compression member, and a strut; substantially as described. 95

6. A bolster having a compression member with top and bottom flanges coextensive with its length and having tapered ends, a tension member lying flat against the lower tapered edge of each end of the compression member and engaging the upper edge of each tapered end; substantially as described. 100

7. A bolster comprising a strut having seats, compression-member I-beams in the seats, and a tension member spaced from the compression member by the strut and engaging the ends of the I-beams; substantially as described. 105

8. A bolster comprising a strut having seats, compression-member I-beams in the intermediate seats on each side thereof, and a tension member spaced from the compression member by the strut and engaging the ends of the I-beams; substantially as described. 110

9. A bolster comprising a strut having flanged seats, compression-member I-beams in the flanged seats, and a tension member spaced from the compression member by the strut and engaging the ends of the I-beams; substantially as described. 115

10. A bolster comprising a strut having seats and spacing portions of the strut providing oppositely-disposed bearings against the webs of the I-beam; substantially as described. 120

11. A bolster comprising a terminally-engaged compression member and tension mem- 125

ber, and castings fitting over the compression and tension members and provided with side bearings bearing upon the top of the compression member, and lower portions bearing 5 against the bottom of the tension member; substantially as described.

12. A bolster comprising a compression member having tapered ends, a flat plate tension member bearing against the under side 10 of the compression member and bent over the ends to engage the top thereof, and a casting on each end of the bolster having a lower por-

tion bearing upon the nether face of the tension member, and an upper portion bearing against the upper face of the compression 15 member; substantially as described.

In testimony whereof I hereunto affix my signature, in the presence of two witnesses, this 13th day of February, 1904.

WILLIAM H. SCOTT.
